UNITED STATES PATENT OFFICE.

CHARLES F. ROOT, OF RAVENNA, OHIO, ASSIGNOR OF ONE-FOURTH TO BYRON O. CONN,
OF MANSFIELD, OHIO.

SAFETY DEVICE.

1,298,566.

Specification of Letters Patent. Patented Mar. 25, 1919.

Application filed August 17, 1914. Serial No. 857,016.

To all whom it may concern:

Be it known that I, CHARLES F. Root, a citizen of the United States of America, residing at Ravenna, in the county of Portage and State of Ohio, have invented certain new and useful Improvements in Safety Devices, of which the following is a specification.

This invention relates to certain new and useful improvements in safety devices for staying machines, though equally applicable to any character or type of machine which has a reciprocating work engaging element, as for example a punching press.

15 The object of my invention is to provide means for automatically rendering the link that imparts movement to the reciprocating work engaging element inoperative when an obstruction is inadvertently or otherwise placed between the element and the anvil and upon engagement of the element with the obstruction.

It is well known in the operation of machines that are provided with a reciprocating work engaging element which exerts a pressure upon an anvil, die or the like, that there is great danger of the operator's fingers being inadvertently placed between the anvil or die and the reciprocating element 30 that exerts pressure to perform the work, with the result that the fingers are crushed or injured.

This is especially true when it is necessary for the operator of the machine to perform work that requires him to place his hands in close proximity to the anvil or die of the machine, and in manipulating the work his hand is liable to be engaged by the reciprocating working element at the time 40 the latter is about to perform its work.

The primary object, therefore, of my invention is to provide means of relieving the pressure that is exerted by the reciprocating element upon the anvil or die to perform the work when an obstruction is interposed between the anvil or die and the reciprocating element.

50 The invention more specifically consists in the combination of a link and pawl which are adapted to impart movement to the reciprocating work engaging element, the pawl being automatically actuated to inter-

lock with the link to provide means for connecting the work engaging element and the driving means whereby to positively operate the work engaging element just prior to and during the time it is performing its work and further to provide automatic means for positively maintaining the pawl released or unlocked with relation to the link during the major portion of the working stroke of the reciprocating work engaging element.

The link and pawl are preferably constructed and actuated to interlock to positively actuate the work engaging element when the latter is about $\frac{1}{8}$ of an inch above the end of its downward stroke, so that if an obstruction, larger than $\frac{1}{8}$ of an inch is interposed or inadvertently placed between the work engaging element and anvil no pressure will be exerted upon the obstruction or anvil except the weight of the work engaging element and its actuating means which latter is supported by the crank of the driving shaft.

A further object of the invention is to provide a safety device which can be applied to machines of the class described without altering or modifying the latter to any material extent.

The above and other objects are attained by the mechanism illustrated in the accompanying drawings, in which:

Figure 1 is a front elevation of a conventional type of staying machine showing the invention applied thereto, and also showing the finger of the operator interposed between the anvil and the reciprocating work engaging element; Fig. 2 is a detail view, in rear elevation of the link and pawl looking from the rear toward the front of the staying machine showing the pawl interlocked with the link in full lines and released therefrom in dotted lines;

Fig. 3 is a side view partly in section, of the link and pawl;

Fig. 4 is a view similar to Fig. 3, of the opposite side of the link and pawl;

Fig. 5 is a side elevation, partly in section of Fig. 1 on a reduced scale;

Fig. 6 is a front elevation of the cam holder; and

Fig. 7 is a side elevation of Fig. 6.

In the drawings the driving shaft 1, is provided with a disk 2 having a crank arm 3, the shaft being journaled in suitable bearings provided in the L-shaped arm 4 of a conventional type of staying machine. Movement is imparted to the driving shaft 1 by the driving pulley 5. A head 6 reciprocates between the ways 7 and has a stud shaft 8 secured thereto.

- 10 The face 9 of the free end of the L-shaped arm 4 is counterbored providing a space 10 surrounding the disk 2 into which space a cam holder 11 is inserted, the latter having an aperture therein to receive the disk 2.
- 15 The cam holder is held in place by screws 12 which pass through apertures 13 and 14 and are threadably engaged with threaded apertures formed in the head. Two cams 15 and 16 are arranged at spaced points on 20 the outer face of the cam holder and are secured thereto in any suitable manner.

The follower or work engaging element 17 is securely attached to the head 6 and cooperates with the usual anvil 18 of a staying machine.

25 For the purpose of connecting the stud shaft 8 of the head to the crank 3 of the driving shaft 1 by means of which reciprocating movement is imparted to the head 6 link 19 which is adapted to be interlocked with and released from a pawl 20 is provided. The link 19 is cut away or reduced on one side thereof at 21, forming a shoulder or abutment 22 which is adapted to contact with the free lower end 23 of the pawl.

30 A bearing or bushing 24 is secured to the upper end of the pawl 20 and has one end thereof slidably projecting into an oblong slot 25 which is formed in the upper part 21 of the link 19. The bushing 24 supports the link and pawl and is loosely mounted upon the crank 3. An aperture 26 is formed in the end 27 of the pawl 19, to provide a bearing for the stud shaft 8 of the head 6. The pawl 20 is provided with fingers 28 and 29, which extend outwardly therefrom as shown.

35 When movement is imparted to the driving shaft 1 the crank 3 imparts a combined reciprocating and oscillating movement to the pawl and link both of which latter in turn transmit a reciprocating movement to the head 6. After the crank 3 has traveled to within about $\frac{1}{8}$ of an inch of the end of its downward stroke the pawl is forced to engage with the abutment or shoulder 22 of the link, (as shown in the full lines in Fig. 2) by the tension of the spring 30 which is fastened to the link 21 by the screw 31. The end of the spring exerts tension on a screw 33 which is secured to the pawl 20, a stop 34 being provided to prevent the pawl from moving out of engagement with the abutment 22 of the link.

40 The finger 28 and cam 16 are arranged so

that when the finger in its upstroke, reaches 45 the point 35 of the cam 16 the pawl and link are within $\frac{1}{8}$ of an inch of the end of their up stroke. When the finger 28 contacts with the cam 16 it forces the end 23 of the pawl out of contact with the abutment 22, as 50 shown in full lines in Fig. 2, to the released position shown in dotted lines in Fig. 2. Upon the finger 28 reaching the end 35 of the cam face 16 the finger 29 is then in contact with the end 36 of the cam 15, thereby 55 keeping the pawl in released position until the finger 29 reaches the point 37 on the cam 15.

60 When the finger 29 reaches the point 37 on the cam 15 the pawl and link are within 65 $\frac{1}{8}$ of an inch of the end of their downward stroke and the follower or work engaging element is within $\frac{1}{8}$ of an inch of the anvil, preparatory to completing its downward movement to act upon the work.

65 As soon as the finger 29 reaches the point 37 of the cam 15 it disengages therefrom, as the throw of the crank 3 carries the finger 29 away from the cam 15 which permits the 70 spring 30 to exert its tension upon the end of the pawl, forcing the latter into locked position, or in contact with the abutment 22 to thereby couple the work engaging element to the driving means.

75 The pawl is engaged with the link just 95 before the work engaging element reaches the end of its downward stroke to act upon the work and continues to be engaged there- 80 with until the finger 28 of the pawl again reaches the point 35 of the cam 16 in its upward stroke. The cams are arranged and 85 secured to the holder so that the finger 28 will contact with the point 35 when the pawl is within $\frac{1}{8}$ of an inch of its upward stroke. This operation is repeated upon each revolu- 90 tion of the driving shaft 1.

95 It will be noted that the link and pawl are not locked together during the major 100 part of the downward stroke of the working element, but only during the final part 105 of such stroke.

110 If an obstruction, as for instance the finger 38, of the operator, is interposed or projected between the work engaging element 17 and the anvil 18, which finger is in thickness in excess of $\frac{1}{8}$ of an inch, the downward stroke of the head will be arrested and the 115 head and link will idle, the crank 3 completing its stroke by passing or moving, with bushing 24, through the slot 25, since the end 23 of the pawl 20 cannot contact with the abutment or shoulder 22 as shown in the 120 dotted lines in Fig. 1 owing to its being in a position where it cannot engage shoulder 22 therefore no pressure can be exerted upon 125 the obstruction.

125 It will be noted that by the aforementioned cam action, the pawl is out of opera-

5 tive connection with or is released from connection with the link during the major portion of its downward stroke and is only permitted to be locked to or engaged with the link at a predetermined point which is preferably just prior to the work engaging element reaching the die or anvil.

10 The point at which the pawl and link are interlocked is, of course, regulated by arranging the cams on the ring in different positions with relation to the fingers 28 and 29 of the pawl. One or more cams or fingers can be used to operate the pawl, the arrangement as shown in the drawings being especially suitable for the conventional type 15 of staying machines now in use.

20 In case the spring becomes disarranged or broken the pawl cannot interlock with the link and the link and pawl are thus maintained positively disconnected or released from each other during the major portion 25 of the downward stroke as stated above, whether the spring is performing its function or not.

25 It will further be noted that the pawl and link virtually form, or constitute a breakable joint incorporated in a connection, which the pawl and link form, between the work engaging element and the reciprocating means, which joint is normally broken and only is made or completed, when no obstruction 30 engages the element, or in other words, when there is free space between the anvil and element.

35 What is claimed is:

1. In combination with a work engaging element and a driver, a multi-part breakable connection between the element and driving means to actuate the former from the latter, automatic stationary cam means to normally maintain said connection broken, and automatic means for causing the connection to be made when there is free space between the anvil and element.

45 2. The combination with a work-performing element and a driving element therefor, of means for actuating the former from the latter, comprising a link and a pawl and stationary cam means for controlling the 50 engagement of the pawl with the link.

55 3. The combination with a work-performing element and a driving element therefor, of yieldable means for actuating the former from the latter, and stationary cam means associated with the driving element for controlling the operation of the yieldable means.

60 4. The combination with a work performing element and a driving element therefor, of a link extending between the same and having sliding connection with one of said elements, a pawl mounted on one of said elements and adapted to engage the link, and a stationary cam arranged to engage

the pawl to prevent such engagement when 65 the path of the work performing element to the work is obstructed.

5 In a machine having a work engaging element and an anvil, driving means for reciprocating said element comprising a link 70 and a pawl, said link being a one-piece member connected at its opposite ends with the work-engaging element and the driving means respectively, and stationary cam means to automatically actuate the pawl 75 to render the work engaging element inoperative to prevent the element from engaging with the anvil when an obstruction extraneous to the work is located in the path of movement of the work-engaging element. 80

6 In a machine having a work engaging element and an anvil, means for reciprocating said element to exert pressure upon the anvil comprising an interlocking link and pawl, and a stationary cam to automatically 85 and positively unlock the pawl from the link to render the work engaging element inoperative.

7 In a machine having a work engaging element and an anvil, means for reciprocating 90 said element to exert pressure upon the anvil comprising an interlocking link and pawl, a stationary cam to automatically and positively unlock the pawl from the link to render the work engaging element inoperative, and means to automatically lock 95 the pawl and link just prior to the engagement of the work by the work-performing element.

8. In combination with a driving means, 100 a reciprocating work-engaging element, means comprising a full link and a pawl to connect said driving means and element, said link being a one-piece member connecting at its opposite ends to the driving means 105 and work engaging means respectively, means to automatically lock said link and pawl to exert a working action upon the work-engaging element at a predetermined point, and stationary cam means to automatically unlock the link and pawl at a predetermined point. 110

9. In a machine having a reciprocating work-engaging element and an anvil, driving means, means comprising a pawl and a full 115 link to connect the driving means and reciprocating work-engaging element, said link being a one-piece member connecting at its opposite ends with the driving means and work engaging element respectively, 120 means to automatically operate the pawl to lock the same with the link, and stationary cam means to unlock the pawl from the link.

10. In a machine having a reciprocating 125 work-engaging element and an anvil, means having a breakable joint for operating the element, means for making the joint when

there is a free space between the element and the anvil and a stationary cam to automatically and positively prevent the making of the joint when the element encounters an obstruction extraneous to the work.

- 5 11. In combination with an anvil, a work-engaging element, driving means therefor, a multi-part breakable and slidable connection between the element and driving means to actuate the element, stationary cam means automatically operative to normally maintain said connection broken, said connection embodying a one-piece link operatively connected at its opposite ends with the driving means and work-engaging element respectively, and automatic means to make connection when there is free space between the anvil and work.
- 10 12. In combination with a work engaging element, and a driver therefor, a multi-part breakable connection between the element and driving means to actuate the former from the latter, and automatic stationary cam means to normally maintain said connection broken.
- 15 13. In a safety device for a machine equipped with a work-engaging element, and driving means, means to couple the driving means and element, and means to allow the coupling means to yield when an obstruction is encountered in its path before it reaches a predetermined point in its working stroke, and to exert pressure upon the work engag-

ing element at a predetermined point in its working stroke including a stationary cam 35 plate operative to normally maintain the coupling means inoperative.

14. In a safety device, in combination with a work-engaging element, a driver and an anvil, a normally uncoupled connection 40 for driving the element from the driver, and means including a stationary cam for normally maintaining said connection uncoupled and for allowing coupling thereof when the path of the element to the anvil is 45 free of any obstruction extraneous to the work.

15. In a safety attachment for machines equipped with a work engaging element, and a driving means, means connected to the 50 driving means and to the element to impart movement to the element and to exert pressure thereon at a predetermined point in its working stroke, said means including a stationary cam plate arranged to prevent pressure from being exerted on the work engaging means upon said means being subjected to pressure before it reaches said predetermined point in its working stroke.

In testimony whereof I affix my signature 60 in presence of two witnesses.

CHARLES F. ROOT.
